FOLDABLE CHAIR CANOPY

Frank Deak, New York, N. Y.

Application April 20, 1939, Serial No. 268,907

2 Claims. (Cl. 135—7.1)

This invention relates to foldable chairs and lounges of novel construction, and has for its main object to provide, in one single unit, a device of the said character which will be easily opened into a desired position or folded into a flat shape confined into a comparatively small space.

My present invention is an improvement on my invention of a Collapsible easy chair, for which a patent application has been filed on March 28, 1939, Ser. No. 264,548.

In my said co-pending application, a collapsible easy chair and lounge has been described and claimed which is composed of three main units, adapted to be secured together or separated from one another, each being adapted to be further collapsed and folded separately and all of them finally being adapted to be placed into a bag. While the device described in my said co-pending application has many important and useful objects and advantages, the present invention is an improvement thereover in many respects.

In the present improved form of my invention, the collapsible or foldable easy chair or lounge, generally of the same construction and of similar uses as has been described in said co-pending application, is formed of one single unit, the parts of which are always secured together and, while it cannot be collapsed into as small a space as the device of said co-pending application, so as to be put into a bag, it may be folded in an easier, simpler and quicker manner, one part thereof being folded over the other, into a flat plate-like formation, and it may similarly be opened up into any of its desired positions.

The present improvement also eliminates a great number of hinges and pivots which were necessary in the earlier device, particularly for the transverse folding of its parts and also eliminates several devices which were used to releasably secure its parts to one another.

Other advantages and objects of this invention will be apparent as the specification of the same proceeds.

In the drawing, accompanying this specification and being a part thereof:

Fig. 1 is a side elevation of my invention in its assembled form set to be used as a lounge;

Fig. 2 is a plan view thereof in the position illustrated in Fig. 1, and

Fig. 3 is a side elevation of my device in its folded position.

Fig. 4 is a sectional detail showing cup shaped receiving elements secured on the rear of the seat of my novel chair, and

Fig. 5 is a fragmentary plan view of a detail showing a pivoted connection between the outer end of a back rest and the inner end of a sun shade used on my device.

5 Referring now to the drawing more in detail by characters of reference, my assembled device is generally indicated by the numeral 20 and is composed of three parts.

The said three main portions of the device are: 10 the central or chair proper portion generally indicated by the numeral 21, a front leg and foot rest portion generally indicated by the numeral 22, and the rear back support and sun shade portion generally indicated by the numeral 23.

15 Taking the three portions, one after the other, and describing each in detail, the central chair proper portion 21 has a seat frame 24 composed of a right hand member 25, and a left hand member 26, a front cross member 27 and a rear cross member 28. Two foldable pivoted front legs 29 and two foldable pivoted rear legs 30 are provided at the respective forward and rearward ends of the side frame members 25 and 26. Collapsible braces 32, well known in this art, are provided 20 between the respective side members 25 and 26, and the legs 29 and 30 so that said legs may be set into their operative positions around their respective pivots (not shown) and secured therein by the braces 32 or said brace members caused 25 to be released and collapsed and the legs 29 and 30 folded up along the inner sides inside of the frame members 25 and 26 as will be understood, 30 and as indicated by the arrows 33 in Fig. 1 and by the dot and dash line showing of said legs in 35 Fig. 2.

Two pivoted arms 34 and 35 are secured on each of the side frame members 25 and 26 as indicated at 34a and 35a, respectively, and an arm rest 36 is secured pivotedly to the upper ends 40 of each pair of arms 34 and 35, as indicated at 34b and 35b, so that said arms 34 and 35, will serve as pivoted link members to permit the raising of said arms and said rest 36 into their operative position, as indicated in Fig. 1. The arms 45 or links 34 and 35 may also be turned downwardly, in the direction of arrows 34c and 35c, alongside of the respective side frame members 25 and 26, the arm rests proper 36 in this case being folded alongside of the mentioned side frame members 25 and 26, and over the folded support arms 34 and 35, into an inoperative position as indicated in the folded view of Fig. 3.

Means are provided for releasably securing the arm rest structure of 34, 35 and 36 in its raised position.

As shown in Fig. 1, at the rear end of each of the respective side frame members 25 and 26 is secured an upstanding plate 37 and the respective rear arms 35 will move in a plane in front of said plate 37. A pin 38 projects from the top portion of the plate and said arm 35 carries a swinging hook device 39, a slot of which will be caused to engage said pin 38 when it is desired to secure the arm 35 in its upstanding position, thereby securing the respective arm rest in its raised position. When it is desired to fold the arm rests alongside the frame members 25 and 26, the hooks 39 will be freed from the pins 38 by swinging them upwardly.

The second, front, foot rest portion 22 of my device is formed of an upper rectangular frame (Figs. 1, 2, and 3) generally indicated by the numeral 42 and composed of the two side members 43 and 44, a front member 45 and the rear member 46.

Two foldable legs 47 are provided at the front of the foot rest structure 22 pivoted as at 48, being adapted to be set in the position shown in Fig. 1 or to be set inwardly inclined, having been rotated around the pivots 48 as indicated by the arrow 49 to a certain degree in which case the foot rest frame 22 will take up a forwardly and downwardly inclined position resting on the ground with its forward end.

A hinge device 50 of obvious construction and operation connects the foot rest frame 22 to the seat rest frame 24 and permits such a downward inclination of said foot rest frame.

Finally, if desired, legs 47 may be entirely folded within the frame 22 alongside its side members 43 and 44, respectively, and the whole frame 22 may be folded on its pivots 50 underneath and alongside the frame 24 as indicated in Fig. 3.

The third or rear section of my device is the back rest and sun shade structure 23 and its construction is as follows:

The back rest proper thereof has two side frame members 51 interconnected by an upper rigidly secured cross member 52 which in the embodiment shown is of a triangular shape in cross section having a rear edge 52a and an upper edge 52b, the lower end 53 of each side member 51 is cut off at an inclination to form a narrow terminating edge for the same, and pivot devices 54 are secured between said lower ends 53 and the side members 25 and 26 of the seat structure proper.

An inner pivoted member 57 is also secured on each member 51, pivoted as at 57a, and sockets 58 are secured at appropriate places at the rear upper end of the seat proper section 21, said sockets being adapted to receive the lower ends 57b of the respective inner member 57, when the members 51 are swung upwardly (arrow 51a) on their pivots 54, and said inner members 57 also are swung somewhat upwardly (arrow 57c) until their lower ends 57b are placed into the sockets 58. In the embodiment shown, the sockets 58 are formed by an appropriate bending of a strip of metal, having inward bottom flanges 58a to rest the ends 57b thereon.

Two adjusting and securing plates 59 are arranged at the upper ends of the respective members 51 to aid in adjusting the position of the sun shade portion of my device generally indicated by the numeral 60. Said sun shade portion is also formed with two side members 61, the lower ends of which are hingedly secured on the respective upper ends of the back rest members 51, as indicated at 62, the opposite faces of the hingedly secured ends of the members 51 and 61 are indi-

cated by the numerals 51a and 61a, (Figs. 2 and 5), their upper edges by 51b and 61b; and their meeting edges by the numeral 62a.

A pivoted frame or sun shade proper generally indicated by the numeral 63, is secured to the upper ends of the side members 61, said frame having two side members 64, a front cross member 65, and a rear cross member 66. Resiliently yielding pivots 67 are arranged between the inner end of the sun shade frame proper 63 and the upper ends of the members 61, the construction of such yielding pivots having a tendency of retaining the sun shade frame proper 63 in any desired position as it is well known in this art.

The use and operation of my device will be obvious from the herein description thereof, but I desire to offer the following remarks to further explain the same:

Normally, my foldable easy chair is assembled 20 and used as a lounge, shown in Figs. 1 and 2.

When it is desired to use my device as an easy chair, it will be set up as follows:

The members 51 will be lifted upwardly on their pivots 54 as indicated by the arrow 51a and, similarly the members 57 will be rocked upwardly on their pivots 57a as indicated by the arrow 57c until their lower ends 57b will be set into the sockets 58.

The back rest members 51 are now in a somewhat rearwardly inclined position, set up to the rear of the seat section proper 21, forming a back for the same, as will be understood. The members 61 of the sun shade section will be arranged in a somewhat forwardly inclined position with relation to the back rest members 51 and secured in such position through the use of the mentioned plates 59. For this purpose, screw pins 68 are provided at the lower ends of the members 61, riding in the arcuate slots 69 of the plates 59. Wing nuts 70 are provided to secure the parts in their desired relative positions.

Similarly, the sun shade frame proper 63 will either be kept in the relative position shown in Fig. 1, or set into any desired position, by turning the same around its yielding but frictionally secured pivots 67.

The foot rest section 22 will be set into its position with legs 47 somewhat turned backwards (arrow 49), and frame 22 inclined downward on pivots 50 (arrow 22a) as will be understood.

In case I want to use my device as a plain arm chair with a back and a sun shade, it will be set into about the position described for the easy chair, but the front foot rest section 22 will be entirely turned underneath the seat frame 24.

When it is desired to fold and store or transport my device, it may be done in the following manner:

The link supports 35 of the arm rest 36 will be unhooked from the plates 37 and the arm rest folded downwardly into the plane on the seat frame 24 and alongside and on the outside of the side members 25 and 26 as indicated by the arrows 34c and 35c, and also in the position of the parts in Fig. 3.

The braces 32 will be released as will be obvious and has been described in my said co-pending application, Ser. No. 264,548, and then legs 29 and 30 will be folded inwardly into said frame, as indicated by the arrows 33.

Preferably, previous to that, the sun frame proper 63 will be folded into the plane of the members 61 as indicated by the arrow 63a.

Thereupon, the back rest support members 57 will be folded into the plane of the back rest

side members 51 as indicated by the arrow 57c, and the whole sun shade proper 60 will be folded downwardly on its pivot 62 to the rear and along-side of the back rest members 51 as indicated by the arrow 60a.

Now, the whole folded back rest and sun shade portion will be folded over the seat proper section 21, as indicated by the arrow 51a, the respective parts finally taking up the position shown in Fig. 3.

It will be seen that my novel foldable easy chair and lounge may be set into any of its desired positions and uses in an easy and quick manner and, it may be folded into the position shown in Fig. 3 in a similarly quick easy manner; in said latter position it being generally in the form of a flat article, substantially of the length and width of the seat frame 24.

The main advantage of the present embodiment of my invention over the one described and claimed in my said co-pending application, Ser. No. 264,548 is that in this embodiment, all the parts are permanently secured to one another and still they may easily be folded into said small simple and flat form shown in Fig. 3 and as easily opened into any desired position and use.

The numerals 83, 84 and 82 indicate supporting straps and fabric covers for the back rest and sun shade proper, which of course, are also employed for the seat and the foot rest (not shown), as will be obvious.

What I claim as new, is:

1. In a foldable chair, having a back rest, a sun shade formed of two sections, a lower section pivotedly secured at the top of the back rest and adapted to be placed in various positions from being forwardly inclined over said back rest to

being folded rearwardly entirely under and along said back rest, an upper section for said sun shade adapted to be placed into various positions with respect to said lower section from being substantially co-planar therewith to being turned forwardly to various inclined positions and finally being entirely folded substantially over and along said lower section, means to secure said lower section in any of its positions, and means between 5 said upper and said lower sections yieldingly and automatically securing said two sections together in any of their said relative positions.

2. In a foldable chair, having a back rest, a sun shade formed of two sections, a lower section pivotedly secured at the top of the back rest and adapted to be placed in various positions from being forwardly inclined over said back rest to being folded rearwardly entirely under and along said back rest, an upper section for said sun shade adapted to be placed into various positions with respect to said lower section from being substantially co-planar therewith to being turned forwardly to various inclined positions and finally being entirely folded substantially over and along said lower section, means to secure said lower section in any of its positions, and means between 15 said upper and said lower sections yieldingly and automatically securing said two sections together in any of their said relative positions.

3. In a foldable chair, having a back rest, a sun shade formed of two sections, a lower section pivotedly secured at the top of the back rest and adapted to be placed in various positions from being forwardly inclined over said back rest to being folded rearwardly entirely under and along said back rest, an upper section for said sun shade adapted to be placed into various positions with respect to said lower section from being substantially co-planar therewith to being turned forwardly to various inclined positions and finally being entirely folded substantially over and along said lower section, means to secure said lower section in any of its positions, and means between 20 said upper and said lower sections yieldingly and automatically securing said two sections together in any of their said relative positions.

4. In a foldable chair, having a back rest, a sun shade formed of two sections, a lower section pivotedly secured at the top of the back rest and adapted to be placed in various positions from being forwardly inclined over said back rest to being folded rearwardly entirely under and along said back rest, an upper section for said sun shade adapted to be placed into various positions with respect to said lower section from being substantially co-planar therewith to being turned forwardly to various inclined positions and finally being entirely folded substantially over and along said lower section, means to secure said lower section in any of its positions, and means between 25 said upper and said lower sections yieldingly and automatically securing said two sections together in any of their said relative positions.

5. In a foldable chair, having a back rest, a sun shade formed of two sections, a lower section pivotedly secured at the top of the back rest and adapted to be placed in various positions from being forwardly inclined over said back rest to being folded rearwardly entirely under and along said back rest, an upper section for said sun shade adapted to be placed into various positions with respect to said lower section from being substantially co-planar therewith to being turned forwardly to various inclined positions and finally being entirely folded substantially over and along said lower section, means to secure said lower section in any of its positions, and means between 30 said upper and said lower sections yieldingly and automatically securing said two sections together in any of their said relative positions, said means to secure said lower section on said back rest in any of its positions, comprising a plate at the upper end of said back rest, a slot in said plate extending to the greater portion of a circle, a bolt on said lower section adapted to travel in said slot, and a releasable lock nut at the end of said bolt engaging said plate.

FRANK DEAK.
